UNITED STATES PATENT OFFICE

CALVIN THURMON MAXWELL, OF HUNTSVILLE, TEXAS

AUTOMATIC DRILLING RIG

Application filed November 23, 1929. Serial No. 409,397.

This invention relates to drilling rigs, and an object of the invention is to provide a bull wheel for association with the drilling rig that gives the maximum hammering effect to the well drilling tool with the minimum of jerking of the drill cable and at the same time increases the number of strokes of the drill bit relative to the rotation of the operating shaft.

Another object of the invention is to provide a pair of resilient pick up sheave wheels for association with the drilling rig on the opposite sides of the bull wheel through which the cable is trained to furnish an uplift as well as a downlift.

With the foregoing and other objects in view the invention consists of a novel construction, combination and arrangement of parts, as will be hereinafter more specifically described and illustrated in the accompanying drawings, wherein is disclosed an embodiment of the invention, but it is to be understood that changes in the same, variations, and modifications may be resorted to without departing from the spirit of the claims here-to appended.

In the drawings wherein like reference characters denote corresponding parts throughout the several views:

Figure 1 is a side elevation of the rig in accordance with the present invention, and partly broken away.

Fig. 2 is a sectional view taken substantially on the line 2—2 of Fig. 1 looking in the direction of the arrows.

Fig. 3 is a diametric section in detail taking through the bull wheel substantially on line 3—3 of Fig. 1.

Referring to the drawings in detail, 4 represents the conventional derrick used in the oil fields for drilling oil wells. The derrick 4 is formed of four upright legs 5 having cross bracings 6 and diagonal bracings 7. On the top of the derrick 4 there is a sheave wheel 8 on a shaft 9, the ends of which are supported in bearings 10 secured on the top cross braces.

A rope drum 11 is rotatably supported on a pair of brackets 12 and are secured to one of the cross braces 6 and the bottom of the

derrick. A pair of spaced transversely extending supporting bars 13 extend across the bottom of the derrick interiorly thereof and another bar 14 is secured between the two bars 13 at its opposite ends.

A shaft 15 is journaled in a bearing 16 on one of the cross bars 6 at the bottom of the derrick and adjacent the inner end thereof it is rotatably supported on a bearing 17 on the cross bar 14. On the outer end of the shaft 15 is a pulley wheel 18 that is connected with a suitable source of power, not shown in the drawings, by the belt 19.

On the free inner end of the shaft 15 is mounted, in a manner to be presently described, a bull wheel indicated generally at 20. In alignment with the inner face of the bull wheel 20 are mounted a pair of sheave wheels 21, 22 on the opposite sides of the bull wheel 20. The sheave wheels 21, 22 are rotatably mounted on the ends of bolts 23, that extend through openings in the cross bars 13. Disposed about the lower projecting ends of the bolts 23 are helical coiled springs 24 which produce tension downwardly on the sheave wheels 21, 22.

The coiled springs 24, at their upper ends, press on the cross bar 13 while the lower ends thereof, press against the heads of the bolts, whereby tension is exerted downwardly on the sheave wheels.

The inner end of the shaft 15 has a reduced spindle 16' and an annular shoulder 12' at the juncture between the reduced spindle 16' and the shaft. A disk 25 has central circular recesses 26, 27 countersunk in its opposite faces. The recesses merge in a heavy rim 28 that is outset with respect to each recess, there being right angle shoulders 29—30 where the peripheries of the recesses merge with the offset rim.

The spindle 16' extends through an opening 31 that is of a larger diameter than the spindle so that the disk 25 will be loosely mounted on the shaft. A pair of ratchet wheels 32, 33 are seated in the recesses 26, 27 with the outer faces of each flush with the side faces of the rim 28 so that the clothing or other extraneous objects will not become entangled therein.

On the peripheral edge of each ratchet wheel 32, 33 are formed a series of ratchet teeth 34, the edges of which are in spaced relation to the shoulders 26, 27. The spindle 16' extends through the central, alined openings in the ratchet wheels 32, 33 which register with the opening 31 and said ratchet wheels are rigidly coupled to the shaft 15 by means of a nut 35 threadably engaging on the outer end of the spindle 16'.

A pair of pawls 36, 37 are seated in pockets 38, 39 formed on the rim 28 and the pockets communicate with the spindle recesses 26, 27 at the periphery thereof. The pawls are journaled on a pin 40 that extends through the rim 28 and are urged outwardly into engagement with the teeth on the ratchet wheels, by means of springs 41.

Projecting laterally from the inner face of the rim 28 is a roller wheel 42 that is rotatably mounted on a pin 43, the inner end of which is anchored to the inner face of the rim. The periphery of the roller is concaved so as to form a groove to receive the cable.

One end of the cable 45 is secured to and wound about the drum 11, and the cable is trained thru the spring tensioned sheave wheels 21, 22 and over the roller 42. As the roller 42 rotates with the rim 28, its path will be in alinement with the cable 45 trained between the sheave wheels. The cable is then trained over the pulley 8 on top of the derrick and on the other free end of the cable is a spring 46, to the lower end of which is attached a drill point 47.

In the operation of the rig, the shaft 15 turns the ratchet wheels 32, 33 in a clock-wise direction and the pawls 36, 37 are engaged with the ratchet teeth 34 to turn the rim 28 in a clock-wise direction. The rim cannot turn counter-clockwise. The tension of the spring is less than the weight of the drill tool so that when the drill tool is at the top of its stroke, as shown in Fig. 1 of the drawings, the weight of the tool causes the rim to rotate faster than the ratchet wheels, thereby allowing the tool to drop with great force.

When the rim is reduced to the same momentum as the shaft, the pawl locks the rim to the ratchet wheel and the roller engages the rope to carry the drill to the top of its stroke again. The parts in Fig. 1 of the drawings, are shown with the drill at the top of its stroke.

By having tensioned sheave wheels on opposite sides of the bull wheel, it has been found that the jerk is lessened on the drop and rebound of the drill point, eliminating wear and tear on the rig. The rotation of the rim taking upon releasing the cable causes the maximum hammering effect, with the least amount of jerking on the cable and increases the number of strokes of the drill point relative to the rotation of the shaft.

It is to be understood that by describing

in detail herein any particular form, structure, or arrangement, tending to limit the invention beyond the terms of the several claims, and the requirements of the prior art.

Having thus described my invention, what I claim as new is:

1. A drill rig including a derrick, a cable drum mounted on the bottom of the derrick having a cable extending therefrom, a sheave wheel on the top of the derrick over which the cable is trained, and a drill point on the free end of the cable; comprising, in combination, a shaft journaled across the bottom of the derrick, a disk loosely mounted on the shaft and having spring-pressed pawls mounted thereon, ratchet wheels rigidly coupled to the shaft and engageable with the pawls to permit the disk to rotate freely in one direction thereon, a pair of spring tensioned sheave wheels mounted on the derrick in alinement with one face of the disk through which the cable is trained for relieving jerking on the cable, and a roller journaled on one face of the disk projecting into the path of the cable to raise the drill point and permit it to fall under its own weight.

2. A bull wheel including a drive shaft, comprising a disk loosely mounted on the shaft and having central recesses in its opposite faces merging in an outset rim, pockets formed in the rim in communication with the recesses, spring pressed pawls mounted in the pockets and urged inwardly into the recesses, a pair of ratchet wheels having peripheral teeth and rigidly coupled to the shaft and seated flush in said recesses with the teeth engageable with said pawls to permit the disk to rotate in one direction only, and a laterally projecting roller on the rim for intermittent engagement with a drill cable.

In testimony whereof I affix my signature.

CALVIN THURMON MAXWELL.
